212,736

CONTAINER FOR A REAGENT DISC DISPENSER

Norbert T. Kuypers, Warren, Mich., assignor to Difco Laboratories, Incorporated, Detroit, Mich., a corporation of Michigan

Filed Aug. 16, 1966, Ser. No. 3,487

Term of patent 14 years

(Cl. D9—218)

FIG. 1

FIG. 3

FIG. 2

FIG. 4

FIG. 5

FIG. 6

FIG. 1 is a perspective view of a container for a reagent disc dispenser showing my new design.

FIG. 2 is a bottom plan view of the container shown in FIG. 1.

FIG. 3 is a fragmentary sectional view taken on the line 3—3 of FIG. 2.

FIG. 4 is a top plan view of the container of FIG. 1.

FIG. 5 is a side elevational view of the container of FIG. 1.

FIG. 6 is a fragmentary sectional view taken on the line 6—6 of FIG. 4.

I claim:

The ornamental design for a container for a reagent disc dispenser, substantially as shown.
